C. H. YOUNG

SHOE STICK

Filed Jan. 10, 1928

Inventor:
Clarence H. Young,
by Harry Worth Young & Harry
H. Young.

UNITED STATES PATENT OFFICE.

CLARENCE H. YOUNG, OF BOSTON, MASSACHUSETTS.

SHOE STICK.

Application filed January 10, 1928. Serial No. 245,715.

My invention, which relates to shoe sticks, and which has among its objects the provision of a stick having reinforced end portions for engagement with a support, will be best understood from the following description when read in the light of the accompanying drawing showing one specific embodiment of the invention, the scope of which invention will be more particularly pointed out in the appended claims.

In the drawing:

Fig. 1 is a perspective view of a stick constructed according to the invention; and

Fig. 2 is a perspective view of the end portion of the stick, constructed according to Fig. 1, in inverted position.

As illustrated the stick comprises a pair of angle-irons having webs 1 arranged back to back and webs 3 substantially in the same plane so as to form a bar of T-shaped cross-section. Herein the angle-irons are secured in assembled relation by rivets or other suitable fastenings 5 which extend through the webs 1, said webs being slightly spaced by washers 7 which surround the rivets.

As shown the bar formed as above described is provided with pairs of pins or pegs 9 for insertion into perforations in lasts to be removably attached to the bar. Conveniently these pins at their ends may have a driving fit with perforations in the webs of the angle-irons.

As shown the webs 1 at the ends of the angle-irons are folded against the end portions of the webs 3 to form portions 11 providing flat surfaces adapted to rest on a support for the stick, the portions 11 being connected to the unbent portions of the webs by inclined portions 13 which preferably are of material extent longitudinally of the angle-irons so as to form braces between the end portions of the angle-irons and the body of the angle-irons.

It is found that where the shoe stick is employed for supporting heavy iron lasts used in connection with fabricating rubber shoes considerable strain is placed upon the end portions 11, with a tendency to bend or break off said end portions. By the present construction the inclined portions 13 in conjunction with the double thicknesses at the ends of the angle-irons prevent such bending or breakage.

It will be understood that wide deviations may be made within the scope of the invention from the embodiment thereof herein

disclosed without departing from the spirit of the invention.

Claims:

1. A shoe stick having, in combination, a pair of angle-irons secured to each other to present webs in substantially the same plane, the remaining webs at the end portions thereof being folded into parallelism with the end portions of the first mentioned webs, and means carried by said angle-irons for attaching lasts thereto.

2. A shoe stick having, in combination, a pair of angle-irons secured to each other to present webs in substantially the same plane, the remaining webs at the end portions thereof being folded into parallelism with the end portions of the first mentioned webs, such folded portions being integral with the unfolded portions thereof, and means carried by said angle-irons for attaching lasts thereto.

3. A shoe stick having, in combination, a pair of angle-irons secured to each other with webs back to back, the remaining webs being substantially in the same plane, the first mentioned webs being bent at the end portions of said angle-irons substantially to lie against the last mentioned webs, and means carried by said angle-irons for attaching lasts thereto.

4. A shoe stick having, in combination, a pair of angle-irons secured to each other with webs back to back, the remaining webs being substantially in the same plane, the first mentioned webs being bent at the end portions of said angle-irons substantially to lie against the last mentioned webs, such bent portions of said webs being integral with the unbent portions thereof, and means carried by said angle-irons for attaching lasts thereto.

5. A shoe stick having, in combination, a pair of angle-irons secured to each other with webs back to back, the remaining webs being substantially in the same plane, the first mentioned webs being bent at the ends thereof to present portions which substantially lie against the end portions of the last mentioned webs, said portions of the bent webs being integrally connected to the unbent portions thereof by bent portions thereof which are of material extent longitudinally of the angle-irons.

6. A shoe stick having, in combination, a pair of angle-irons arranged to form a bar of T-shaped cross-section, said angle-irons se-

cured in assembled relation by fastenings passing through the facing webs thereof, said webs being folded at the ends thereof to present portions lying substantially against the 5 end portions of the other webs, said first mentioned portions being integrally connected to the unfolded portions of the webs by inclined

portions of material extent longitudinally of the angle-irons, the webs of said angle-irons forming the flange of said T carrying pins 10 for securing lasts to said bar.

In testimony whereof, I have signed my name to this specification.

CLARENCE H. YOUNG.
